VOTING MACHINE

Alvin N. Gustavson, Bemus Point, N. Y., assignor
to Automatic Voting Machine Corporation,
Jamestown, N. Y., a corporation of Delaware

Application May 27, 1942, Serial No. 444,640

2 Claims. (Cl. 235—54)

1

This invention relates to an improvement in voting machines and more particularly to a mechanism for requiring a voter to indicate and cast a complete ballot, and includes structure of the nature of my abandoned application, Serial No. 195,722, filed March 14, 1938.

In an election for representatives to general assembly, representatives to conventions, or in any other office group election, there are more candidates up for election than there are offices to be filled. Certain of the candidates must always be defeated and others nominated or elected. In elections of this nature the voter is instructed to cast his ballot for the same number of candidates as there are offices to be filled in a given office group. Little or no effect on the outcome of an election would occur if only a few voters failed to cast their ballots as instructed, but it was found that a group of voters, by pre-arrangement, could defeat the purpose of an election of this nature by casting their ballots for only one candidate instead of a number of candidates equal to the number of offices in the office group. In this manner a particular candidate would receive votes equal in number to that of the group of voters and the other candidates would receive none. Thus the favored candidate would be the equivalent of twice the number of votes ahead of any other candidate with respect to a given group of voters. Inasmuch as this practice is not only unethical and contrary to the intent of the election laws, it became necessary to provide a mechanism for controlling this condition in elections involving candidate groups.

The present invention is directed to means for controlling balloting in elections involving candidate groups and comprises a mechanism which serves to prevent a voter from recording his ballot and leaving the voting booth without first having complied with the election laws concerning candidate group balloting.

Prior to this invention, in the election of candidates to office groups, a voter could comply with the election requirements, thereby satisfying any protective mechanism provided for this purpose, and indicate to an election official that his ballot was complete. The election official would then raise the entrance knob for the purpose of locking the voting machine against further balloting and unlocking a lever operable by the voter, to register his ballot and open the curtains of the booth. Subsequently to the entrance knob being raised by the election official and prior to the voter's operation of the registering lever, it was possible for the voter to withdraw any or all of

2

the ballots he previously had indicated and which had satisfied the protective mechanism of the voting machine to the extent of allowing the election official to raise the entrance knob. Thus the protective mechanism could be circumvented and it became evident that the voting machine must be under protective control from the time a voter enters the booth until he leaves it.

The present invention serves to prevent the withdrawing of ballots subsequent to the time a voter has indicated his ballot is complete and ready to be registered, and this constitutes the principal object of the invention.

Another object of the invention is to provide a mechanism for a voting machine which functions to control and require proper balloting subsequently to the release or withdrawal of control by an election official.

Other and further objects of the invention will be more fully understood from a consideration of the following specification, taken in conjunction with the accompanying drawings; and in which

Fig. 1 is a rear elevation of one modification of the invention applied to a voting machine;

Fig. 2 is a horizontal sectional view taken substantially on the line 2—2 of Fig. 1;

Fig. 3 is a horizontal sectional view taken substantially on the line 3—3 of Fig. 1;

Fig. 4 is a fragmentary view, partly in section, showing that portion of the mechanism adapted to engage and control movement of interlocking straps in main and auxiliary interlocks;

Fig. 5 is a view similar to Fig. 4 showing interlocking straps held in voted position by a bar forming a part of the invention;

Fig. 6 is a view of a part of the mechanism shown in Fig. 1, with the elements in a position assumed when the entrance knob has been raised and a voter has operated the curtain closing lever;

Fig. 7 is a further view showing the position of the parts of the mechanism during their return to normal position;

Fig. 8 is a fragmentary rear elevational view of another modification of the invention applied to a voting machine;

Fig. 9 is a vertical sectional view, partly enlarged, taken substantially on the line 9—9 of Fig. 8, and shows the parts in inoperative position;

Fig. 10 is a vertical sectional view, similar to Fig. 9, showing the parts in full line in partly operated position;

Fig. 11 is a fragmentary perspective view showing a strap interlocking bar;

Fig. 12 is an enlarged vertical sectional view taken substantially on the line 12—12 of Fig. 11; and

Fig. 13 is an enlarged vertical sectional view of a modification form of the structure shown in Fig. 12.

Reference is now had to the drawings wherein the invention is shown applied to a voting machine, a portion of which is generally indicated by the reference numeral 10. The machine includes side and base walls 11 and 12. Adjacent the base wall is a main interlock 13 having main interlocking straps 14. Since the present invention has to do particularly with balloting in office groups, an auxiliary interlock 16 is provided. This interlock includes auxiliary straps 17 joined in any conventional manner to and operable by straps 14.

An entrance knob 18 is located exteriorly of the voting machine and is limited to vertical movement through the provision of a shaft 19 which is mounted in a suitable slot 21 in the wall 11 of the machine. A sleeve 22 and strap 23 are mounted on the shaft 19. A shaft 24, secured to strap 23, mounts one end of a rod 26. The rod 26 extends downwardly along the wall 11 and is joined at its lower end through a pivot member 27 to one end of a rocker arm 28. Arm 28 is fitted with a rod 29 which is projectable through an opening in one or more plates when a voter has manipulated the prescribed number of candidate indicators on the face of the voting machine and the related interlocking straps 14 and 17.

Secured to the wall 11, beneath the entrance knob 18, is a bracket 31. This bracket has an upwardly extending arm 32. Mounted on the arm 32 is a pivot pin 33 which supports a bell crank 34. An arm 36 of the bell crank 34 is pivotally connected by a pin 37 to a bracket 38 that is rigidly secured to the rod 26. The other arm 39 of the bell crank is pivotally connected with one end of an extensible member 41 which comprises a pair of straps 42 and 43. These straps are formed with longitudinally extending slots 44 and 46. A pin 47 on strap 42 projects into slot 46 and a further pin 48 on strap 43 projects through slot 44. An expansion spring 49 is secured at one end to pin 48 of strap 43 and at the other end to a further pin 51 on strap 42.

The free end of strap 43 is joined through a pivot pin 52 to a rod 53. It will be noted that this rod parallels straps 42 and 43 and at one end is pivotally joined to a cam 54 through a pin 56. The cam 54, at its lower end, is pivotally mounted on bracket 31 and includes surfaces 57, 58, and 59. Fixed to the other end of rod 53 is a plate 61. The free end of this plate is connected through a pivot pin 62 with an arm 63 of a bell crank 64. A central supporting member 66 in the voting machine mounts a horizontally disposed bracket 67 to which the central portion of the bell crank 64 is joined by a pivot pin 68. An arm 69 of the bell crank is pivotally connected with one end of an angle bar 71. One or more links 72 have pivotal connection at one end with the bar 71 and are pivotally anchored at the opposite ends to a fixed portion of the machine. The purpose of link 72 is to guide the bar 71, bell crank 64 serving to transmit movement of rod 53 to bar 71 in a direction perpendicular to the movement of said rod. Each of the interlocking straps 14 is formed with a lug 13. These lugs all extend in

the same direction. Bar 71 is adapted to move into position above or beneath lugs 13 for the purpose of preventing movement of the straps 14 out of the position they occupy at the time the bar is manipulated.

Adjacent the side wall 11 of the machine is a vertically positioned bar 74 which extends upwardly and is connected in any conventional manner with the lever that is adapted to be operated by a voter to open or close the curtains of a voting booth. Adjacent the entrance knob 18, one end of a strap 76 is pivotally joined to the bar 74. This strap is formed with an offset to cause the lower portion 77 thereof to approach wall 11. The portion 77 projects between a pair of guides 78 mounted on one face of the bracket 31. Adjacent the offset of the strap 76 is a pin 79. Under certain circumstances of operation hereinafter set forth, pin 79 is adapted to contact surfaces 57, 58, and 59 of cam 54.

Having described the structure of the invention, its use in connection with the operation of a voting machine is as follows: It is to be assumed that the voting machine 10 is arranged to handle the election of candidates in an office group where there are a limited number of offices available and a greater number of candidates are seeking nomination or election to these offices. In accordance with the election laws, a voter must cast his ballot for a candidate for each of the offices of the group. When a voter enters the voting booth, the election official raises the entrance knob 18. In the usual mechanism of the voting machine, knob 18 functions, through strap 23, to release the lever by which the voter may enclose himself in the booth and unlock the machine for voting. However, since the present invention is connected with the entrance knob, an adjustment of certain parts thereof also takes place. It will be noted that strap 26 is connected with the entrance knob and, therefore, this strap will move upwardly, causing arm 28 to pivot and rod 29 to project through a neutral position opening in one or more plates located in the auxiliary interlock 16. As the strap 26 moves upwardly, it causes bell crank 34 to pivot about pin 33 on bracket 31. This rotational movement of the bell crank moves member 41, which in turn causes rod 53 to move toward the left as viewed in the drawings. One end of rod 53 is joined to the cam 54 and, consequently, this cam will swing into the position shown in Figure 6 of the drawings. The rod 53 is also connected through plate 61 with bell crank 64 and causes this bell crank to rotate about pivot pin 68 and move the angle bar 71 to occupy a position directly over lugs 13 of the straps 14.

As the voter moves the lever to close the curtains and unlock the machine for voting, bar 74 moves downwardly, causing strap 76 to move downwardly, pin 79 is thus brought into contact with surface 57 of cam 54. Since this surface is inclined, the cam will be rotated clockwise about its pivot and move rod 53. This movement of rod 53 causes angle bar 71 to momentarily move out of position above lugs 13. It is to be noted that the entrance knob 18 is still in raised position and bell crank 34 and member 41 are in the position shown in Figure 7 of the drawings. Movement of rod 53, without moving bell crank 34 or strap 26, is possible through the provision of the extensible member 41 which, as heretofore described, comprises relatively slidably spring held straps 42 and 43. As the pin 79 moves from off surface 57 onto surface 58, the tension of

spring 49 causes cam 54 to commence moving toward the left as viewed in the drawings. This movement continues until the pin has moved onto the notched surface 59. This action of the pin 79 and cam 54, it will be understood, takes place during the curtain closing operation and the parts of the invention, when the voting machine is ready for use, assume the position shown in Figure 6 of the drawings.

During the curtain closing operation, the relatively extensible parts 43 and 44 have functioned and bar 71 momentarily withdrawn from its position overlying the lugs of the straps. No advantages are obtained by this functioning of the parts during the curtain closing operation. However, during the curtain opening operation, as is well known in voting machines of this type, it is necessary to first secure the actuated straps against voter manipulation, register the vote indicated by the voter and, third, return the straps to their original inoperative position. The relatively extensible parts, which permit withdrawal of bar 71, function during the curtain opening operation following registering the indicated vote on the counters, and permit movement of the straps to their original inoperative position. It might be assumed that withdrawal of bar 71 would withdraw control of the machine over the possibility of a voter's changing his preference, but it is to be borne in mind that by the time such a possibility exists the voter's indicated ballot has already been registered, and any attempt to manipulate the voting indicators would in no wise affect the original intended vote.

When the election official lowers the entrance knob 18, shaft 29 is withdrawn from the auxiliary interlock 16. With the lowering of entrance knob 18, the cam 54, rod 53, and bar 71 return to the position indicated in Figures 1, 2, and 4 of the drawings and the interlocking straps are thus free to be moved. The voter may now cast his ballot for a candidate for each of the offices listed on the face of the voting machine. As the voting operation takes place, certain of the interlocking straps 14 and 17 are raised and assume the position shown in Figure 5 of the drawings. If the voter has properly cast his ballot, certain of the interlocking straps 14 and 17 will actuate a control mechanism in the auxiliary interlock 16 by causing one or more plates thereof to register certain openings with shaft 29. The voter now indicates to the election official that he has completed balloting and said official again raises the entrance knob 18. The strap 26 moves upwardly, rocking arm 28 and moving shaft 29 downwardly into engagement with certain plate openings in the auxiliary interlock 16. If the voter has not properly cast his ballot, the entrance knob cannot be fully raised because the shaft 29 will not be engageable with openings in the plates of the auxiliary interlock. Strap 26 again causes bell crank 34 to swing about pivot 33 and, through rod 53 and bell crank 64, moves bar 71 toward the interlocking straps 14. It will be noted (see Figure 5) that straps 14 have been raised by manipulation of indicators on the face of the voting machine and that said bar has now moved into position beneath lugs 73 and prevents movement of the straps 14 from voting to non-voting position. In other words, once the voter has indicated to the election official that his choice of candidates has been made, and the official has raised the entrance knob 18 for the purpose of allowing him to open the curtains of the booth, record his vote, and leave the machine, he can-

not change his mind concerning his ballot and move any indicators from voting to non-voting position, due to the fact that these indicators are directly connected with straps 14 and these straps are prevented movement by bar 71. Upon movement of the curtain lever to open position, bar 74 moves upwardly and, through strap 76, causes pin 79 to ride upwardly along the surfaces of cam 54 and the parts of the device return to the position shown in Figure 1 of the drawings, thus preparing the mechanism for control of the next voter.

Since bar 71 extends substantially the full length of the machine, it is effective not only to prevent movement of straps 14 of a given group, but all of the straps of the voting machine, whether they are in a group the mechanism is intended to control or not. It is conceivable that a voter might fail to fully actuate one or more straps not set up in a given group, and such actuation might be such as to cause the vertical edges of one or more lugs 73 to become directly aligned with the vertical edge of the upper flange of the bar 71. Under such circumstances the bar 71 could not move into position above or below the lugs and its usefulness as a means of preventing undesired movement of the straps would be nullified. Although it is true that a strap 14 would not be properly actuated and a corresponding candidate indicator on the face of the machine would not have been fully moved into vote indicating position, it is conceivable that voters unfamiliar with machine voting might fail to fully move the candidate indicators and effect full movement of the corresponding straps 14, thereby creating the condition mentioned.

A modification of the invention is shown in Figures 8 to 13, inclusive, and in this form the device provides against damage or incomplete operation of the machine by utilizing the bar 71 as a support for one or more plates that engage the lugs of the straps. These plates are of different lengths to accommodate different size groups and may be placed on the bar 71 to effectively control a group, regardless of its position on a voting machine.

Reference is now particularly had to Figures 8 to 12, inclusive, wherein such a modification of the structure is shown. In this instance, main interlocking straps 80 are provided. These straps each include conventional means for connecting the auxiliary straps 17 thereto. Additionally, they include pointed lugs 81 having upper and lower surfaces 82 and 83, respectively, and a shoulder 84, which is a continuation of surface 83 and formed on the under edge of the lug. Straps 80, in all other respects, are identical with straps 14 and, of course, interlocks 13 and 16 are as shown and described in the previous modification.

One or more plates 86 are mounted on the horizontal flange of the bar 71. The number, length, and disposition of these plates correspond to the number of groups to be controlled, their location on the voting machine, as well as their length; by which is meant the number of straps involved in a group. Each plate is formed with a wedge shaped front edge 87, and one or more downwardly inclined cams 88 are located adjacent this edge. The plate is mounted on the bar 71 upon pins 89 that project through the slots 91 of the plate. Any suitable removable means, such as cotter pins 92, serve to prevent displacement of the pins. Between the head 93 of each pin and the under face of the horizontal flange of the bar 71 may be located a small spring 94. The spac-

ing of the head 93 from the bar 71 determines the extent to which plate 86 may be tilted, and the spring 94 serves to return this plate to full surface contact with the upper flange of the bar 71 after such tilting. The edge of the plate 86, when 5 in inoperative position, is flush with the vertical flange of the bar 71. One or more strip or other suitable springs 96 are secured to the vertical flange of bar 71 by pins 97. These springs (see Figure 8) extend laterally along the flange of the 10 bar and thence upwardly to form a projection 93 that engages the rear edge of the plate 86. Any rearward movement of plate 86, within the limits prescribed by pins 89 and slots 91, tensions springs 96 and causes them to subsequently return the 15 plate to unoperated position.

It is clearly evident that the entrance knob 18 cannot be actuated if less straps than the number required to be actuated in a group have been so actuated. In the event a voter has only partially actuated one or more of the required number of straps 80, such actuation being sufficient to spread the rollers of the auxiliary interlock 16 and make possible entry of pin 29 into the sliding plate actuated by said rollers, the main strap 80 may 20 have been raised to no greater extent than indicated in Figure 10 of the drawings. However, this position of the strap 80 is such as to bring the pointed end of the lug 81 slightly above the point 87 of a plate 86. Thus, when the entrance knob 18 is raised and bar 71 is caused to move plate 86 into engagement with the lugs of one or more such partially actuated straps, the plate will strike the inclined surface 83 and move the incompletely actuated strap 80 to the position it should have 25 occupied had it been fully actuated in the first instance. Plate 86 is capable of completing movement of insufficiently operated straps 86, not only because of its contact with the lug, but also because such contact causes rearward movement of plate 86 with respect to bar 71, and as such movement takes place, cams 68 move onto the upper flange of the bar, raising the forward edge of the plate and giving additional movement to the straps 80. Plates 86 may therefore be said to not 30 only secure the straps in partially operated position against improper return to inoperative position, but also move said straps to fully operated position to prevent damage from occurring to their connected parts during the operation of registering a vote.

When utilizing the plates 86 as a means of engaging the lugs of the straps, bar 71 must be positioned farther to the rear of the machine than it would normally be positioned if directly engageable with the lugs of the straps. It is contemplated, however, that the position of bar 71 may be reversed such, for example, as shown in Figure 13, and thus the bar, operating structure, and supports would be identical with the structure shown in Figure 1. Plate 86 in this

modification extends beyond the vertical flange of the bar 71 and is mounted for limited horizontal movement with respect to the bar by the pin and slot structure 89-91. Attached by pins 99 to the horizontal flange of the bar are springs 100. These springs are similar to springs 96 and serve a corresponding purpose.

It is to be particularly noted, in connection with the modification shown in Figures 8 to 13, inclusive, that should a voter fail to actuate a strap 80 to an extent such that the under side of a lug 81 would be engaged by plate 86, such actuation would be insufficient to permit movement of the entrance knob 18, as pin 29 would not enter an opening in the sliding plate controlled by the interlock rollers. Furthermore, should any straps be slightly moved, plate 86, if the group voting is satisfied as to number through actuation of their straps, will contact upper surface 82 of lugs 81, returning them to fully unoperated position.

Although applicant has shown and described only two modifications of a mechanism in a voting machine which serves to prevent a voter changing his vote subsequently to his indication to an election official that his vote is complete, it will be understood by those skilled in the art that modifications of the structure herein described may be made and are contemplated insofar as they are within the spirit and scope of the invention as set forth in the hereunto annexed claims.

Having thus set forth my invention what I claim as new and for which I desire protection by Letters Patent is:

1. In a voting machine having a manually operable control member and a plurality of operable straps having offset portions, a mechanism for securing said straps against movement from either operated or inoperated position, said mechanism comprising a bar movable to engage the offset portions in either position of said straps, a rod joined to said control member, yieldable means operably connecting said bar with said rod, further means connecting said bar with a further bar, said further bar being operable to move said yieldable means and at least momentarily withdraw said bar from engagement with said offset portions without affecting said control member.

2. In a voting machine having a control member movable to an operated position and a plurality of operable straps having offset portions, a mechanism for securing said straps in operated position comprising a bar engageable with said offset portions when said straps are in operated position, yieldable means operably connecting said bar with said control member, and further means connected with said bar, said further means being operable to at least momentarily move said yieldable means and withdraw said bar from engagement with said offset portions without affecting said control member.

ALVIN N. GUSTAVSON.
